(57) **CLAIM**

The ornamental design for a mermaid tail blanket with halter top and zippered end, as shown and described.

DESCRIPTION

FIG. 1 is a perspective view of a mermaid tail blanket with halter top and zippered end showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom view thereof with the zippered end being unzipped;

FIG. 9 is a perspective view thereof worn on a standing person; and,

FIG. 10 is a perspective view thereof worn on a sitting person.

The broken lines are for environmental purposes only and form no part of the claimed design.
